US00D960507S

(12) United States Design Patent (10) Patent No.: US D960,507 S
(45) Date of Patent: * Aug. 16, 2022

(54) PANTS

(71) Applicant: Pairadize GmbH, Vienna (AT)

(72) Inventors: Julia Baessler, Vienna (AT); Stephanie Baessler, Vienna (AT)

(73) Assignee: Pairadize GmbH, Vienna (AT)

() Term: 15 Years

(21) Appl. No.: 29/755,399

(22) Filed: Oct. 20, 2020

(30) Foreign Application Priority Data

Apr. 21, 2020 (EM) 007826292

(51) LOC (13) Cl. 02-02

(52) U.S. Cl.

USPC D2/742

(58) Field of Classification Search

USPC D2/742, 731, 712

CPC A41D 1/06; A41D 1/08

See application file for complete search history.
